UNITED STATES PATENT OFFICE.

ELIE CANNES, OF NEW YORK, N. Y.

PNEUMATIC-TIRED WHEEL.

1,086,805.

Specification of Letters Patent. Patented Feb. 10, 1914.

Application filed February 24, 1913. Serial No. 750,217.

To all whom it may concern:

Be it known that I, ELIE CANNES, a citizen of the United States, residing in the borough of Manhattan, city of New York, State of New York, have invented new and useful Improvements in Pneumatic-Tired Wheels, of which the following is a specification.

My invention relates to the tires of vehicle wheels, and more particularly to that type embodying the pneumatic feature wherein the pneumatic tube or tubes are thoroughly protected against puncture, and has for its objects to provide certain improvements in the construction of the same as will be hereinafter more definitely pointed out and claimed.

In the accompanying drawing: Figure 1 is a view in side elevation of a portion of a wheel having my improved tire thereon, the same being partly broken away to show the interior construction. Fig. 2 is a transverse sectional view taken on the line 2-2, Fig. 1. Fig. 3 is a sectional view taken on the line 3-3, Fig. 1.

Similar numerals of reference denote corresponding parts in the several views.

In the said drawing the reference numeral 1 denotes the wheel rim, of wood or metal, to which the spokes 2 are connected in any suitable manner. Said rim is preferably continuous, and permanently secured thereto at definitely spaced intervals are the substantially I-shaped spacing members 3, the same having their inner flanges disposed in recesses or mortises in the rim 1 so as to lie flush as to their upper surfaces with the outer face of said rim, as shown. Disposed in the spaces between said I members 3 are the inflatable tubes 4 forming the pneumatic feature, the same being each provided with an inflating valve 5 of any suitable construction.

Bolted to the sides of the rim 1, preferably by through bolts 6, are the side plates 7 and 8, the plate 7 being preferably a continuous plate, while the plates 8 are in section, one for each tube 4, so that any one of the same may be separately removed to obtain access to its inclosed tube 4. Said plates 7 and 8 are inturned at 9 at their outer edges to engage plates 10 fastened to the inner faces of segments 11 formed preferably of wood, said segments being recessed in their sides at 12 to accommodate the inturned flanges 9, as shown. Each of said

segments is surfaced with a tread of rubber or other resilient material 13, and has formed therein preferably two through slots 14, in which are disposed transverse bars 15 bolted at their ends to the inturned flanges 9 of the side plates 7 and 8. Bolted to the sides of the segments 11 and co-extensive in length therewith are the cover plates 16, the same serving to inclose at all times the recesses 12 in the segments 11 and prevent ingress of dirt thereto.

In operation the inflatable tubes 4 support the segments 11 in the position shown in Fig. 2 and yield successively as their supported segments contact with the ground, the engagement between the flanges 9 and plates 10 serving to limit the outward movement of said segments, while the side plates 7 and 8 effectually limit the lateral displacement of said tubes 4. By reference to Fig. 1 it will be seen that the ends of the segments 11 are recessed at 17 on their inner sides, and the ends of the plates 10 project to underlie the outer flanges of the I members 3, the same, together with the transverse bars 15, effectually retaining said segments against longitudinal movement with respect to their underlying tubes 4.

In order to more effectually prevent access of moisture and dirt to the tubes 4, I prefer to dispose between the edges of the flanges 9 and the surfaces of segments packings 18 of leather, rubber or the like, the same to be fastened to said flanges 9. I also prefer to line the inner faces of the plates 7 and 8 where they contact with the tubes 4 with a coating 19 of rubber, leather or the like, to protect said tubes from undue heating due to friction.

While I have shown but a single row of tubes 4 and segments 11 on the wheel rim 1, it will be understood that for use with heavy vehicles two or even more rows of tubes 4 and segments 11 may be employed, the same being disposed side by side on a common wheel rim.

Having thus described my invention, what I claim as new and desire to secure by Letters Patent is:

1. The combination with a wheel rim, of spacing members fixed thereto at intervals, inflatable tubes disposed longitudinally between said spacing members, tread segments resting upon said tubes, and segmental side plates inclosing said inflatable tubes co-extensive with said tread segments and re-

- movably fixed to said rim and interlocking with said tread segments to limit the outward movement and prevent lateral movement of the latter.
5. 2. The combination with a wheel rim, of I-shaped spacing members fixed thereto at intervals, inflatable tubes disposed longitudinally between said spacing members, tread segments resting upon said tubes and recessed at their inner sides and ends, plates fixed to the inner faces of said segments and projecting beyond the recessed sides and ends thereof, said plates at their ends engaging beneath the outer flanges of the spac-
- 10

ing members, and segmental side plates co-extensive with said tread segments and removably fixed to said rim and inclosing said tubes and having inturned flanges engaging over said segment plates to limit the outward movement and prevent lateral movement of the latter. 15

In testimony whereof, I have hereunto set my hand in the presence of two subscribing witnesses.

ELIE CANNES.
